UNITED STATES PATENT OFFICE

140,628

DESIGN FOR A SUPPORT FOR TOILET ACCESSORIES OR THE LIKE

Alta R. Batten and James R. Batten,
Cleveland, Ohio

Application August 26, 1944, Serial No. 115,053

Term of patent 3½ years

(Cl. D4—3)

To all whom it may concern:

Be it known that we, James R. Batten and Alta R. Batten, citizens of the United States, residing at Cleveland, county of Cuyahoga, and State of Ohio, have invented a new, original, and ornamental Design for a Support for Toilet Accessories or the like, of which the following is a specification, reference being had to the accompanying drawings, forming part thereof.

Fig. 1 is a front view in elevation of a support for toilet accessories, showing our new design;

Fig. 2 is an end view in elevation of the support for toilet accessories shown in Fig. 1;

Fig. 3 is a view in section of the support for toilet accessories, the section being taken on line 3—3 of Fig. 1;

Fig. 4 is a view in section, the section being taken on line 4—4 of Fig. 1; and

Fig. 5 is a rear view in elevation of the support for toilet accessories shown in Fig. 1, the lower right hand corner being shown broken away.

We claim:

The ornamental design for a support for toilet accessories or the like, substantially as shown.

ALTA R. BATTEN.
